(57) **CLAIM**

The ornamental design for a Y-split connector, as shown and described.

DESCRIPTION

FIG. 1, is an isometric view of the Y-split connector, showing my new design;

FIG. 2, is a side elevational view thereof;

FIG. 3, is a side elevational view thereof, rotated 90 degrees from the side elevational view of FIG. 2;

FIG. 4, is a top view thereof; and,

FIG. 5, is a bottom view thereof.
